UNITED STATES PATENT OFFICE

2,468,844

SPRING COMMUTATOR

Carl Henry Sutherland, Pittsburgh, Pa., assignor
to Westinghouse Electric Corporation, East
Pittsburgh, Pa., a corporation of Pennsylvania

Application January 10, 1948, Serial No. 1,520

2 Claims. (Cl. 171—321)

1

My invention relates to the mechanical mounting of commutator-cylinders for dynamo-electric machines, and it has more particular relation to a new spring-mounting for holding the commutator-bars in place.

My invention is an improvement over the disk-spring commutator of the Moore Patent 1,826,628 of October 6, 1931, and the commutator-process of the Graybrook Patent 2,379,145 of June 26, 1945, both patents being assigned to the Westinghouse Electric Corporation.

An object of my invention is to provide a spring-commutator for railway-locomotive traction-motors, or other purposes, which will allow the rotor-core to be lengthened by approximately $1\frac{3}{4}$ " while using the same stator-frame, end-brackets and commutator-bars.

A further object of my invention is to provide a spring-commutator mounting in which the disk-spring is mounted at the rear of the commutator, where there is available room, but in which the rear V-ring is in one piece with the commutator-spider, which is solid on the armature-spider, so that the commutator-necks do not move axially toward and away from the armature-core so as to break the commutator-leads, as in certain previous rear-spring commutators.

A further object of my invention is to provide a spring-commutator having not only a rear-mounted disk-spring, but also a plurality of axially extending studs, which are subject to elongation in series with the disk-spring deflection, so as to decrease the change in the pressure which is exerted on the commutator-bars due to temperature-changes and speed-changes.

A still further object of my invention is to provide a disk-spring commutator which can be retightened, after it is assembled in the finished armature, without requiring the armature to be placed under a press, as in previous designs, in order to relieve the pressure on the tightening-means before the latter can be drawn up more tightly.

With the foregoing and other objects in view, my invention consists in the novel parts, structures, combinations and methods of assembly and use, hereinafter described and claimed, and illustrated in the accompanying drawing, the single figure of which is a longitudinal sectional view of the top half of the commutator-end of a railway locomotive traction-motor embodying my invention, with the brushes omitted for the sake of clarity.

My new spring-commutator is shown in the drawing as being applied to a series single-phase

2

railway-motor having a stator-frame 1, carrying a stator-core 2, which in turn carries the various field-windings 3 of the motor. The end of the stator-frame 1 carries an end-bracket 4, which is provided with a bearing 5 for supporting the motor-shaft 6. The shaft 6 carries the rotor or armature-spider 7, on which is mounted the armature-core 8 in cooperative relation to the stator-core 2. The armature-core 8, in turn, carries the armature-windings 9, having commutator-leads 10 which are connected to the necks 11 of the respective commutator-bars 12 which make up a cylindrical-surfaced commutator 13. The extending portions of the armature-windings 9 and leads 10, which extend out toward the commutator 13 from the armature-core 8, are supported on a core-endplate or cell-support 14 having a forwardly extending cylindrical shoulder 15 under which extends the rear V-ring 16 of the commutator-supporting means.

The commutator bars 12 are provided with the usual V-grooves 17 at each end, and are held in place by means of front and rear V-rings 18 and 16. One of these V-rings is integral with a commutator-spider 19 which is rigidly secured to a portion of the armature-spider 7, so that it is immovable with respect to both the armature-core 8 and the commutator-leads 10 of the armature-winding 9. The other V-ring slides axially on the commutator-spider 19 so as to yieldably hold the commutator-bars 12 in place.

As set forth in the previously mentioned patents, and as shown at the rear end of my commutator 13, a disk-spring 21 is used to apply spring-pressure to the movable V-ring. Heretofore, the disk-spring has been placed at the same end of the commutator as the movable V-ring, and when an attempt has been made to put the disk-spring, and the movable V-ring, at the rear, where there is ample room for the spring, the axial movement of the movable rear V-ring has transmitted itself to the commutator-necks, resulting in so much breakage in the commutator-leads that this mounting-construction had to be abandoned. This meant that the disk-spring and the movable V-ring had to be placed at the front of the commutator, where there was no room for it, because of the protruding inner or rear end 22 of the bearing 5, necessitating a lengthening of the frame, or a shortening of the core, in order to make room for the disk-spring at the front end of the commutator.

In accordance with my invention, I make the rear V-ring 16 integral with the commutator-spider 19, the front V-ring 18 being movable, and

I place the disk-spring 21 under the immovable rear V-ring 16, with the top peripheral edge of the disk-spring engaging a rear surface or shoulder of the rear V-ring. I place a pressure-ring 25 with a shoulder in engagement with a rear inner surface or shoulder of the disk-spring 21, said pressure-ring 25 being movably mounted on the armature-spider 7, so that it can slide axially in a forward and backward direction. The pressure-ring 25 is provided with a plurality of forwardly extending studs or elongated tension-members 30, the rear ends of which are firmly secured in the pressure-ring 25, said studs being spaced at uniform intervals around the pressure-ring 25. These studs 30 pass loosely through suitable holes 32 in the commutator-spider 19, and through similar holes 33 in the inner part of the movable front V-ring 18, and the front ends of these studs 30 are threadedly engaged by nuts 36 which are tightened up against a front surface or shoulder of the movable front V-ring 18. The studs 30 are preferably necked down, as shown at 40, at places where they are not threaded, so that the necked-down diameter of the studs is about equal to the diameter at the bottoms of the threads in the studs, thereby increasing the resilience of the studs.

In operation, it will be apparent that the studs 30 transmit the pressure of the disk-spring 21 to the movable V-ring 18, permitting the disk-spring 21 to be placed at the rear, where there is room for it, and permitting the movable V-ring 18 to be at the front of the commutator, so that the immovable V-ring 16 may be at the rear, where it prevents the objectionable axial movement of the commutator-necks 11 as the movable V-ring 18 moves in and out, due to temperature-changes, speed-changes, and spring-pressure adjustments.

My invention also overcomes another difficulty that has become so accustomed to, that its avoidance has been looked upon, for all practical purposes, as one of the impossibles. Heretofore, in assembling disk-spring commutators, it has been customary to place the commutator under a press, so as to place the spring under a strain, and then to tighten a retaining-nut for holding the spring in place, in its strained position. This procedure was not particularly objectionable in the original assembly of the commutator, before it is assembled in the finished armature, but the necessity for placing the entire armature under a press was not at all desirable, in cases where it was necessary to retighten the commutator in the finished armature. This necessity for the use of a press (not shown) resulted from the fact that the disk-spring of the prior commutators was at the front of the commutator, and was held in place by a large nut which was threaded on the commutator-spider, and which had such a large peripheral friction-surface, in engagement with a front surface of the disk-spring, that it could not be turned when the spring was under stress, as will be apparent from the previously mentioned patents.

In my improved disk-spring mounting, however, the compression of the disk-spring 21 is maintained by a plurality of studs 30, having individual, relatively small, nuts 36 on their

front ends, and the peripheral extent of the frictional abutment-surfaces of each of these small nuts 36 is so small that the nuts can be turned when they are pressing tightly against the front surface of the movable front V-ring 18, and an equal stress on all of the studs may be assured by tightening the nuts with a torque-wrench (not shown).

My new spring-commutator also provides additional resilience or yieldability, because the studs 30 are resilient, in addition to the resilience of the disk-spring 21. At pressures in common use on spring-commutators, the studs elongate some .015 to .018 inch and the spring deflects some .050 to .060 inch. The additional yield which is provided by the studs 30 thus reduces the difference in the V-ring pressure which is applied to the commutator when the commutator-bars expand or contract due to temperature-changes or speed-changes.

And the foregoing important operational advantages of my invention are in addition to the still more important space-saving structural advantage that my disk-spring 21 is placed at the rear, where there is room for it, while retaining the use of an immovable rear V-ring which avoids the lead-breakage which heretofore resulted from placing both the movable V-ring and the spring at the rear.

While I have shown my invention in but a single exemplary form of embodiment, I wish it to be understood that various structural changes may be made, by way of substitution of equivalents, and the addition or omission of certain parts, without departing from the essential spirit of the invention. I desire, therefore, that the appended claims shall be accorded the broadest construction consistent with their language.

I claim as my invention:

1. A spring-commutator assembly comprising a plurality of commutator-bars having V-grooves in their ends, and having commutator-lead-engaging parts at their rear ends, an immovable commutator-spider having an immovable V-ring at its rear end and an axially movable V-ring at its front end, said V-rings engaging the V-grooves, a disk-spring at the rear end, a peripheral edge of the disk-spring engaging a rear surface of the immovable rear V-ring, a pressure-ring having a peripheral edge in engagement with a rear inner surface of the disk-spring, a plurality of forwardly extending studs carried by said pressure-ring, and nuts on the front ends of said studs in engagement with a front surface of the movable front V-ring.

2. A dynamo-electric machine having a spring-commutator assembly as defined in claim 1, said machine having a stator-frame having a part carrying a bearing which extends close to the stud-nuts, and said machine having a rotor-member having a winding and a winding-support having a forwardly extending cylindrical shoulder which provides a space, below it, for the rear end of the rear V-ring and for the disk-spring and pressure-ring.
